US00D936917S

(12) **United States Design Patent** (10) **Patent No.:** **US D936,917 S**
Li (45) **Date of Patent:** **** Nov. 23, 2021**

(54) **DOG TRAINING DEVICE**

(71) Applicant: **Shenzhen Huihongyuan Technology Co., Ltd.**, Shenzhen (CN)

(72) Inventor: **Li Li**, Hunan (CN)

(**) Term: **15 Years**

(21) Appl. No.: **29/709,436**

(22) Filed: **Oct. 15, 2019**

(30) **Foreign Application Priority Data**

Aug. 5, 2019 (CN) 201930420522.0

(51) **LOC (13) Cl.** **30-99**

(52) **U.S. Cl.**

USPC **D30/199; D10/104.1**

(58) **Field of Classification Search**

USPC ..... D30/151-155, 144, 199, 160; 119/792-798, 850, 855-859, 863-865, 119/654, 905, 907, 815, 712, 802, 784, 119/769, 760, 776, 862, 908, 860, 119/719-721; 242/381.1-381.2, 385.4, 242/378.3, 376.1, 385.1, 916, 601, 570, 242/405, 404, 371, 223, 170, 388.1, 242/405.2, 377, 381.3, 381.6, 405.3, 242/388.6, 384.7, 382, 396.1, 404.1, 380; 362/108; 33/767, 769, 414; D12/400; D3/229, 230, 207, 208, 215; 40/1.5, 455, 40/640, 303; 206/63.3, 459.5, 702, 408; D6/515; D8/358, 360, 347, 360.1, 359, D8/356, DIG. 1; D24/145, 167, 186, 146, D24/169; D10/57, 72, 106.1, 104.1, D10/104.2, 109.2, 70, 97, 98, 78, 65; D20/28; 224/666, 678; 16/445; 283/74, 283/70; D11/232, 200, 216, 1, 2, 86, 87, D11/201, 206-210, 212-215, 218; 24/163 K, 122.3, 323, 702, 600.4-600.7, 24/163 R, 169-171, 173, 177-179, 191, 24/194, 195, 197, 200, 303, 616, 635,

(57) **CLAIM**

The ornamental design for a dog training device, as shown.

DESCRIPTION

FIG. 1 is a front elevational view of a dog training device showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is another perspective view thereof.

1 Claim, 8 Drawing Sheets
